UNITED STATES PATENT OFFICE.

ALEXANDER WINTON, OF LAKWOOD, OHIO, ASSIGNOR TO THE WINTON GAS ENGINE & MANUFACTURING COMPANY, OF CLEVELAND, OHIO, A CORPORATION OF OHIO.

CAM-SHAFT STRUCTURE AND OILING MECHANISM FOR INTERNAL-COMBUSTION MOTORS.

1,339,839.

Specification of Letters Patent. Patented May 11, 1920.

Original application filed September 26, 1914, Serial No. 863,704. Divided and this application filed June 17, 1916. Serial No. 104,315.

To all whom it may concern:

Be it known that I, ALEXANDER WINTON, citizen of the United States, residing at Lakewood, in the county of Cuyahoga and State of Ohio, have invented certain new and useful Improvements in Cam-Shaft Structures and Oiling Mechanism for Internal-Combustion Motors, of which the following is a specification.

10 This invention relates to improvements in internal combustion motors and particularly to devices of that character using fuel oil and operating under high compression.

More specifically the invention relates to 15 an internal combustion motor comprising a plurality of cylinders, air inlet and exhaust valve mechanism therefor, operating devices for said valve mechanism comprising rockers and cams arranged upon a cam shaft, 20 the supports and bearings for the cam shaft being arranged in sections or separable units, together with certain mechanism for maintaining a proper oil level in a suitable trough arranged about the cam shaft and 25 the bearings therefor.

The invention may be further briefly summarized as consisting in the construction and combination of parts hereinafter set forth in the following drawings, description and 30 claim.

Referring to the drawings Figure 1 is a side elevation of the engine showing the cam shaft side; Fig. 2 is an end elevation of the first cylinder and is a view taken behind the 35 governor with parts broken away and in section; Fig. 3 is a detail sectional view, showing the valve mechanism in each cylinder head; Fig. 4 is a plan view of a unit of two cylinders with the head of one removed 40 and the head of the other broken away, other parts being shown in plan and section; Fig. 5 is an elevation of the upper portion of the same unit with parts broken away and in section; Fig. 6 is an elevation of a portion 45 of the cam shaft side of the motor, showing the oil system; Fig. 7 is a section through the cam shaft trough; and Fig. 8 is a top plan view of a section of the cam shaft and trough with the cover removed.

50 In carrying out my invention any preferred form and construction of parts may

be employed so long as they possess the necessary characteristics, but I have shown one arrangement which is effective, and in such embodiment the several parts will first be 55 described, followed by a description of the complete operation.

The crank case may be of any desired construction or arrangement, but, as illustrated, comprises a lower base 1, mounted upon a 60 suitable support 2, carrying the upper crank case member 3. These parts inclose a suitable crank shaft upon which is mounted a balance wheel 4. The forward portion of the crank case contains suitable gearing and 65 other mechanism (not shown) for operating an air pump 5, to furnish air under pressure for the fuel mixture which is supplied to the engine. The crank shaft is also connected to a governor 6, whose particular construction is unimportant, but which is provided with the usual grooved member 7 for controlling the fuel supply, as will later appear.

The upper half 3 of the crank case is provided on the exhaust side of the engine in the upper corner with a longitudinally disposed channel or passage 8 communicating with a suitable pipe 9 preferably leading to a point outside of the building, so as to 80 muffle the noise of the air intakes. At each cylinder said channel has a side port 10 for a purpose to be described.

Six cylinders are preferably employed, each comprising a main cylinder body 11 85 provided with a suitable water jacket 12 and a lower supporting flange 13 adapted to be secured to the upper member 3 of the crank case. Each cylinder, at its upper end 4, is faced off to receive the cylinder head structure to be described. At the upper end of the cylinder its face is cut away at diametrically opposed points, as at 14, to provide space for the operation of the valves, as will later appear. On the exhaust side each cylinder jacket is provided with a finished portion 15, having an outlet port 16 for a purpose to be described. At a lower point on the same side of the cylinder, the jacket is provided with a finished boss 17 forming a 90 seat to receive a flange 18 in turn connected to a hand operated valve 19, this valve in 95 100

turn being connected to a water supply manifold pipe 20, leading to a suitable water pump (not shown). Each cylinder is provided on the exhaust side and preferably 5 toward one side with a cast metal air inlet member 21, having a channel 22 therein communicating with one of the ports 10 and whose upper end is finished with the top of the cylinder. Diametrically opposed to this 10 air inlet member is a pet-cock or relief valve 23 of any desired form, in communication with the interior structure through a suitable port 24, shown in dotted lines in Fig. 4. This pet-cock and relief valve may be utilized for any of the purposes to which such 15 devices are applicable.

Each cylinder is provided with a head 25 which is hollow to form a water space. Integral with the wall of the head are suitable 20 vertically disposed ribs 26 provided with openings for receiving suitable bolts or studs 27, for holding the head in place. The head is provided upon its bottom with an exhaust valve opening 28, having a seat 29 and with 25 an air inlet opening 30 provided with a seat 31. A suitable exhaust housing 32 extends into the hollow head and establishes communication between the opening 28 and an opening 33 in the exhaust elbow 34 extending 30 out beyond the side of the cylinder. This elbow and housing are formed integral with the head and with a water jacket elbow portion 35, these parts terminating in a horizontally disposed flange 36 beyond the side 35 of the cylinder.

The opening 30 communicates with an air inlet housing 37 formed integral with the head and extending out and in communication with an air inlet elbow 38, the lower 40 edge of said elbow being finished and being flush with the lower edge of the head and arranged in position to communicate with the opening 22 in the air inlet member 21. The water jacket portion of the exhaust 45 elbow structure is provided with suitable ports 39, preferably three in number, extending through the flange 36, as shown in Figs. 4 and 5. Each head 25 is also provided with a water outlet connection 40 terminating in a horizontally disposed flange 41, as shown in Figs. 1, 2, and 4.

Any suitable form of primary air and fuel inlet mechanism may be employed but I have shown one arrangement in the drawings which consists of a valve stem 42, a valve 43, a spring 44 and a thrust washer 45 secured to the stem in any suitable manner. This valve is moved downward and opened to permit the inlet of the primary 50 air and fuel.

The exhaust opening 28 and the air inlet opening 30 are both provided with valve mechanism, and since the mechanism in both instances is the same a description of one 55 will suffice for both. Each valve structure

comprises a stem 46 guided in the head and having at its lower end a mushroom valve 47 adapted for engagement with the seat. The upper end of the stem is guided in the head and is surrounded by a spring 47^a, this 70 spring engaging the head at one end and at the other end engaging a washer 48 held in place upon the stem by a split ring 49 arranged in a groove in the stem.

Each cylinder head is held in alignment 75 upon its corresponding cylinder by a reduced portion 51 engaging within a recess 52 formed in the upper part of the cylinder, and is forced into place by the bolts or studs 27. When the cylinder head is in place, the 80 opening in the air inlet elbow 38 communicates with the opening 21 as hereinbefore stated.

So far as the exhaust manifold structure is concerned, the cylinders are arranged in 85 pairs, each provided with a manifold having a water circulation about the same, and each of these manifold units or sections consists of an outer casing 54 provided at each end with a flange 55 and on the side toward the 90 cylinder with other flanges 56, (Fig. 2), the latter being provided with openings 57 communicating with the openings 16 in the cylinders. The other end of one of the manifold units is provided with a plate or cover 95 54' while the manifold unit at the opposite end of the engine receives a face plate 54'', to which is connected an exhaust pipe 54''. The flanges 55 at the ends of each section are extended inward beyond the wall 54 and 100 are integral with an exhaust housing 58 provided with an exhaust opening 59, this opening communicating by suitable openings 60 with the exhaust opening in the corresponding exhaust elbow. The upper surface of 105 the manifold member is finished to receive the flanges 36 which are held in place by suitable bolts or cap screws 61. Between the walls 54 and 58 there is a chamber 62 which constitutes a water jacket in communication with the openings 57 and with the jacket formed in the exhaust elbow by suitable openings 63 in alignment with the 110 openings 39.

From the foregoing it will appear that the 115 exhaust from the cylinders passes through the opening 59 and out at the end to the next manifold and that the circulating water to each pair of cylinders passes up from the inlet around the exhaust manifold from 120 whence it passes to the head jacket structure and from each head it passes through the member 40 to a discharge connection 64 leading to a discharge manifold 65, the connection 64 being secured by a flange 66 to 125 the flange 41.

Each of the cylinders is provided at a point opposite to the exhaust with a finished boss 73 and it is upon these bosses of the several cylinders that the cam shaft bear- 130

ing and trough structure is mounted. This cam shaft bearing and trough structure is made up in sections in a manner similar to the exhaust, that is, there is one section for each pair of cylinders, each section comprising a trough consisting of a bottom 74 provided with brackets 75 secured to the corresponding bosses 73. The trough also includes a front side 76 and a rear side 77, the ends of each trough section being open. Within each trough are three bearings 78, one near each end and one between the two cylinders, and these bearings support, so far as this section is concerned, a cam shaft 79 provided adjacent each cylinder with an exhaust cam, a primary fuel and air inlet cam and a main air inlet cam, these cams being properly timed in order to bring about the proper operation of the engine, as will be readily understood. Secured upon the top of the trough section is a cover comprising a rear portion 83 and an outside portion 84, these two portions being provided with notches 85 and upwardly extending flanges 86 above each of the cams to permit the entry of the depending portions 87 of the valve rocker arms 88. These rocker arms are all alike and each is provided with a roller 89 for engaging the cam, and at its opposite end with an adjusting screw 90 for engaging the corresponding valve stem. In order to take up any lost motion between each roller 89 and its cam, each of the rocker arms is provided with a spring 91 engaging a projection 92 on the underside of the arm and the corresponding portion of the cylinder head, the spring being prevented from buckling by a suitable pin 93.

Each of the trough sections is further provided at its ends with flanges 94, the flanges of adjacent sections being secured together to form a continuous trough and support for the cam shaft throughout its entire length and the trough is closed in the case of the two end trough sections by a suitable plate 95 on the one end and a gear casing member 96 on the opposite casing and being adapted to receive suitable gearing of any desired arrangement connected to the shaft operating the governor so that the drive from the engine to the governor conveys the drive to the cam shaft.

The oiling system comprises any suitable pump arranged in the bath of oil in the crank case, but I have shown a gear pump comprising a casing 97 provided with a stuffing box 98 receiving the vertical shaft 99 driven from the engine. On the lower end of this shaft is a gear similar to and meshing with the gear 100 mounted in the pump case. Secured to the under face of the pump casing is a suitable plate 101. This pump receives oil on one side in an obvious manner and forces it into a supply pipe 102 which leads up through the casing

to a manifold pipe 103 arranged against the back wall 77 of the cam shaft trough. This manifold is connected by short connections 104 with each of the bearings 78. In operation, the oil pump elevates the oil to the bearings and as it escapes about the shaft 79 it collects in the trough. Its level is maintained by a stand pipe 105 extending up through the bottom 74 of trough and to a point near the bottom of the shaft 79. The lower end of this pipe 105 passes down to the crank case so as to deliver the overflow of oil back to the supply.

Fuel supplied to the engine is delivered under pressure to the mechanism for feeding it to the several cylinders, and any suitable means may be provided for supplying it in this manner, it being sufficient, so far as this application is concerned, to state that the fuel is delivered under pressure to the feeding mechanism now to be described, and as more fully described and shown in my prior application for explosive engine filed September 26, 1914, Ser. No. 863704, of which this application is a division. Secured to the bracket 75 and against the side of the trough section at the governor end of the engine is a fuel pump housing 109 provided with a cover plate 110 upon its front and a cover plate 111 upon its top. Mounted within the upper part of the housing in a horizontal plane with the cam shaft and in parallel alinement therewith is a pump shaft 112 provided with a plurality of eccentrics 113 one for each cylinder, and with a driving gear 114 meshing with a driving gear 115, shown in dotted lines in Fig. 2, this gear 115 being arranged upon the cam shaft. Engaging each of the eccentrics 113 is an eccentric strap 116 pivotally connected to a pump plunger 117 passing through a suitable stuffing box 118 into a pump barrel 119 formed in the housing 109. Within the casing 109 is an eccentric strap, plunger and barrel for each cylinder, and each of these barrels communicates by a passage 120 with a passage 121 in turn leading to a discharge check valve member 122 communicating with a pipe 131 leading to the corresponding cylinder. The passage 120 of each fuel pump leads to a corresponding inlet passage 133 communicating by way of a check valve 134 with a fuel supply passage 135.

The engine operates in an obvious manner and it will be seen that in operation any back-lash between the rocker arms and their operating cams will be taken up by the springs 91 and that the proper level of oil for the cam shaft is also maintained.

Having thus described my invention, what I claim is:

In an explosive engine, a plurality of cylinders, each having a cylinder head provided with an air inlet and an exhaust, an air inlet valve controlling the air inlet, an

exhaust valve controlling the exhaust, an operating device for each of said valves, a cam shaft trough suitably mounted, cam shaft bearings arranged within said trough, 5 a cam shaft mounted in said bearings, cams carried by said cam shaft for actuating said valve operating devices, a fuel pump hous-

ing carried by said trough and communicating therewith whereby the oil level in the trough is maintained in the fuel pump housing, and a fuel pump arranged within said housing below the oil level therein. 10

In testimony whereof I affix my signature.
ALEXANDER WINTON.
